UNITED STATES PATENT OFFICE.

FREDERICK L. FULLER, OF TRENTON, NEW JERSEY, ASSIGNOR TO THE NATIONAL CASH REGISTER COMPANY, OF DAYTON, OHIO, A CORPORATION OF OHIO, (INCORPORATED IN 1906.)

ADDING MECHANISM FOR CASH-REGISTERS, &c.

981,633.

Specification of Letters Patent. Patented Jan. 17, 1911.

Application filed February 5, 1907, Serial No. 355,817. Renewed April 9, 1909. Serial No. 488,979.

To all whom it may concern:

Be it known that I, FREDERICK L. FULLER, a citizen of the United States, residing in the city of Trenton, in the State of New Jersey, have invented certain new and useful Improvements in Adding Mechanism for Cash-Registers, &c., of which the following is a specification, reference being had to the accompanying drawings, forming a part hereof.

This invention relates to adding mechanisms for cash registers and the like and has for its object to produce a mechanism of this character which shall be both positive and definite in action, without liability to overthrow of any of the adding wheels, while at the same time the totalizer shall be simple in construction and easily applied to and removed from the cash register or other machine in connection with which it is employed.

In accordance with the invention the totalizer or adding mechanism is moved into driving engagement with the main driving gears of the register or other machine and is moved out of engagement therewith during the carrying or advance of each number wheel or disk one step or number through the completion of the rotation of the wheel of next lower denomination.

Other features of the improvement will be more particularly referred to hereinafter. The invention is illustrated as embodied in a convenient and practical form in the accompanying drawings, in which—

Figure 1 is a view partly in transverse section and partly in elevation of so much of a cash register of a well known type as is necessary to enable the application of the invention to be understood, the improved adding mechanism itself being shown in end elevation. Fig. 2 is a partial view similar to Fig. 1, but showing the adding mechanism disengaged from the driving gear. Fig. 3 is a rear elevation of the adding mechanism, showing also the main driving shaft of the register. Fig. 4 is a detail view of a portion of the totalizer or adding mechanism in longitudinal section. Fig. 5 is a detail view in section on the irregular plane indicated by the line 5—5 of Fig. 3. Fig. 6 is a similar view but showing the parts in slightly different positions. Fig. 7 is a detail view in section on the irregular plane indicated by the line 7—7 of Fig. 3. Fig. 8 is a detail view in perspective of the cam shaft. Fig. 9 is a detail inside elevation showing differential mechanism and mechanism for restoring and latching the same.

In the drawings the invention is illustrated as applied to a cash register of a well known type described in Patent No. 915,090 granted to Frederick L. Fuller, March 16, 1909. The details of construction of the cash register are not material to the present invention, except so far as the register is provided with a series of main driving gears suitably mounted in the frame *a* and severally rotated in the operation of the register to an extent proportionate to the number indicated by the register and to be added by the totalizer to the previous total recorded upon the totalizer. One of such driving gears is shown at *b*, being itself driven in one direction by the spring *b'* and being restored to normal position while the spring *b'* is recharged by manually operated devices shown in Figs. 1 and 9. A manually operable lever *c* is fast to a shaft *c* which also has fast thereto a pair of arms *o* carrying a restoring rod *p* extending across the path of movement of tails *q* of a set of segment gears *r*. These segment gears mesh with a set of gears *b*² geared to the set of driving gears *b'* by pinions *b*³ and shafts *b*⁴, and each is provided with a pin *s* for engagement with a stop *t*. Rotation of gears *b* by action of springs *b'* is normally prevented by the stops *t*, and pawls *u* engaging gears *b*. The stops *t* are loosely pivoted on a shaft *v* and are each integral with an arm *w* curved downwardly in the rear of pins *x* on value keys *y*. Therefore when any value key is depressed the arm *w* in the respective bank is rocked inwardly thereby rocking stop *t* out of the path of pin *s* for the segment *r* of such bank but the segment is still prevented from moving by reason of the engagement of pawls *u* with gears *b*. The pawls *u* are all fast to the shaft *v* which also has rigidly secured thereto an arm *z* extending across the rear of a pin *z'* on a release key *z*². Therefore action of gears *b* for the banks in which keys have been depressed does not take place un-

til the release key is depressed and the gears b for banks in which keys are not depressed remain in their normal position by reason of their respective stops t not being moved 5 out of engagement with pins s . The value keys are depressible into the paths of pins r' carried by the segments r and thereby serve to regulate the extents of movement of the segments and driving gears b . They are 10 held in their depressed position by spring actuated detents x' until the operation of lever c' preparatory to another registration. Operation of lever c' by rocking arms o of shaft c causes rod p to engage the tails q of 15 segments r rocking the segments back to original positions thereby tensioning springs b' and by means of a slight overthrow at the end of its stroke momentarily raises detents X thereby releasing the depressed keys 20 which are then driven to their outer positions by coiled springs surrounding their shanks. The rod p has a slight free movement at the beginning of its stroke before engaging any of the tails q in order to allow 25 time for disengaging the totalizer from gears b before return movement of the gears.

The totalizer is arranged so as to be normally in operative engagement with the driving gears b so that the several number 30 wheels thereof shall be driven forward by their respective driving gears, and so as to be moved out of operative engagement therewith, during the backward rotation of the driving gears, if they have such backward 35 rotation, and as to permit the carrying from one number wheel to the next in order while the number wheels are out of operative engagement with the driving gears. As shown, the totalizer is supported by a frame which 40 comprises end plates d , d' , rods d^2 , d^3 , and d^4 , fixed in the end plates and a bar d^5 . The frame is mounted to swing on the crank shaft c and the bearings of the end plates d , d' on the shaft are respectively provided 45 with removable caps d^6 , so that the adding mechanism as a whole can be easily applied to or removed from the register or other machine with which it is used. The frame is pressed normally in such a direction as to 50 throw the totalizer out of engagement with the driving gears and for this purpose the springs b' which drive the gears b may be attached to the lower edge of the bar d^5 , below the axis of oscillation of the frame. 55 For the purpose of moving the totalizer into operative engagement with the driving wheels and maintaining it there and for permitting the disengagement of the adding mechanism from the driving gears, there is 60 mounted in the frame of the totalizer a cam shaft e provided at one end with a pinion e' which is engaged by a gear segment e^2 fixed on the crank shaft c so as to move therewith. The shaft e also carries a cam

e^3 which co-operates with a stop e^4 on the 65 main frame a , so that when the cam e^3 is in the position shown in Fig. 1, the totalizer is held in operative engagement with the gear wheels b , while if the cam e^3 be turned to the position represented in Fig. 2, the totalizer will be permitted to swing from the driving gears b out of operative relation therewith, under the influence of the springs b' , as shown in Fig. 2. The cam e^3 bears 70 always against the stop e^4 and the springs b' are maintained always under tension. The cam shaft e has a further function which will be referred to hereinafter, but its independent utility in rocking the totalizer 75 into mesh will be apparent from the above. 80

Mounted loosely on the rod d^2 of the adding frame are the number wheels or disks f , f' etc., bearing the figures from zero to 9 inclusive upon the periphery of each. Secured to each number wheel of the totalizer 85 to rotate therewith is a driving pinion g which is adapted to be engaged by the corresponding driving gear b and is also engaged by a hold pawl g' mounted on the rod d^3 to prevent backward rotation of the 90 pinion. Each number wheel above the units wheel has also secured to it to rotate therewith a carrying pinion h , preferably on the opposite side of the number wheel from the driving pinion g . Each number wheel is 95 also provided with a carrying pin i to co-operate with a four-point wheel or star wheel k which is mounted to rotate on the rod d^4 of the frame and has secured thereto, to rotate therewith, a notched detent wheel l for co-operation with a detent spring l' , and a second four-point wheel or star wheel m which co-operates with the carrying pinion h for the next number wheel in order. The 100 detent wheel l is suitably notched, as is well understood, and engaged by the spring l' so as to prevent accidental movement of the four-point or star wheels.

The cam shaft e is provided with a series of cam disks n , n' , etc., co-operating with the 110 several star-wheels m and spirally set or notched so that in the rotation of the cam shaft e the several cam disks shall act in succession upon the respective star wheels m .

While the totalizer is in operative engagement with the driving wheels, the rotation of the number wheel through its driving pinion g causes the pin i carried by the number wheel to act upon the star wheel k so as to move the star wheel m from the position shown in Fig. 5 to the position shown in Fig. 6 in which the lower point or tooth of the wheel m has been moved into the notch of the disk n far enough to be engaged by the toe of the cam when the cam is rotated. 120 125

It will be understood that when the parts are in the position shown in Fig. 5 both of the points of the wheel m which are adjacent

- to the cam disk n are clear of its periphery so that the cam disk can rotate freely without disturbing the star wheel until it is moved into the position shown in Fig. 6. 5 As soon as the forward movement of each of the driving gears b has been completed, the advance of each of the number wheels having been thereby accomplished, the crank c' is operated for the purpose of restoring 10 the driving gears b and their connections to normal position and recharging the springs b' . The beginning of the movement of the crank throws the high part of the cam e^3 from the stop e^4 and permits the totalizer to 15 be moved away from the driving wheels b and the pinions g out of engagement therewith, so that the totalizer is not affected by the movement of the driving gears b back to normal position. 20 If any of the number wheels f , f' , etc., was made to complete a rotation during the preceding forward movement of the driving gear b , the carrying pin i of such number wheel shifted the star wheels k and m 25 from the position shown in Fig. 5 to the position shown in Fig. 6, as already described. The continued movement of the crank shaft, after the disengagement of the numbering mechanism from the driving 30 gears, then causes the toe of each cam disk n , n' , etc., in succession to engage the proximate point of the corresponding star wheel m , if it has been shifted as described, and to produce a further forward rotation of 35 such star wheel, as clearly shown in Fig. 7, carrying with the star wheel m the star wheel k and the detent wheel l . The further movement of the star wheel m causes the tooth thereof adjacent to the pinion h to 40 engage such pinion and rotate it through one step, thus advancing the number wheel carried with such pinion h through one space, thus representing the increase of the corresponding denomination due to the addition of ten units to the next lower 45 denomination.
- The spiral arrangement of the cams n , n' , etc., as shown in Fig. 8, provides for the carrying from a wheel of one denomination to 50 the wheel of the next higher denomination after the carrying has been effected for all the wheels of lower denominations. During the continued movement of the crank shaft and parts connected therewith, after the carrying has been effected, and during the return movement of the crank shaft or connected parts, the several cam disks n , n' , etc., move without disturbing the star wheels which are indeed locked from further accidental movement by the coöperation of the high periphery of the cam disks with two points of the corresponding star wheel. No further movement of any of the star wheels takes place until, as already described, one 55 or more of the star wheels has been advanced 65 by the rotation of the number wheels. As the crank shaft returns to normal or zero position and the parts of the machine are placed in readiness for another operation cam e^3 , coöperating with the stop e^4 , throws 70 the totalizer back into engagement with the driving gears. 75 It will be understood that various changes in details of construction and arrangement can be made to meet varying conditions of use and that the invention is not restricted to the precise construction and arrangement shown and described herein.
- I claim as my invention:
1. The combination with driving gears, 80 springs connected to the driving gears and charged by movement thereof in one direction and a totalizer comprising number wheels actuated by the driving gears and carrying mechanism, of a movable frame supporting the totalizer, said springs acting normally upon the frame to move the totalizer out of operative relation with the driving gears, and means to move the frame with the totalizer into operative relation 85 with the driving gears and to actuate the carrying mechanism when the adding mechanism is out of operative relation with the driving gears.
  2. The combination with driving gears, 90 springs connected to said driving gears and charged during the movement of the driving gears in one direction and a totalizer comprising number wheels actuated by the driving gears and carrying mechanism, of a 95 frame supporting the totalizer and mounted to swing upon an axis parallel with the axis of the driving gears, said springs being connected to the frame and acting upon the frame to swing the totalizer out of operative 100 relation with the driving gears and means to swing the frame into operative relation with the driving gears and to actuate the carrying mechanism when the totalizer is out of operative relation with the driving 105 gears.
  3. The combination with driving gears, 110 springs connected to said driving gears and charged by movement thereof in one direction and a totalizer comprising number 115 wheels actuated by the driving gears and a carrying mechanism, of a movable frame supporting the totalizer, said springs acting normally upon the frame to move the totalizer out of operative relation with the driving 120 gears, a cam to move the frame with the totalizer into operative relation with the driving gears and means to actuate the carrying mechanism when the totalizer is out of operative relation with the driving 125 gears.
  4. The combination of driving gears, totalizer, carrying mechanism, a movable frame for supporting the totalizer and the

carrying mechanism and devices carried by the frame for actuating the carrying mechanism and for moving the frame with relation to the driving gears.

5 5. The combination of driving gears, totalizer, carrying mechanism, a swinging frame mounted upon an axis parallel with the axis of the driving gears, a shaft mounted in said frame, means carried by said shaft 10 for actuating the carrying mechanism, and means carried by said shaft for moving the frame with relation to the driving gears.

6. The combination of driving gears, totalizer, carrying mechanism, a shaft parallel 15 with the axis of the driving gears, a swinging frame mounted on said shaft and supporting the adding mechanism and the carrying mechanism, a cam shaft mounted in said frame and provided with means to 20 actuate the carrying mechanism and with a cam to move the frame with relation to the driving gears and gearing between the first named shaft and the cam shaft.

7. In a machine of the class described, the 25 combination with driving gears, of a swinging frame, a totalizer and a transfer operating shaft carried in said frame, an operating device for said transfer shaft, and a cam carried by said transfer shaft and 30 serving when said shaft is rotated by the operating device to engage said totalizer with said driving gears.

8. In a machine of the class described, the combination with a swinging frame, and a 35 totalizer and a transfer operating device therefor carried by said frame, of an operating mechanism for said transfer device, a cam moved by said transfer operating mechanism, a stationary piece engaged by 40 said cam, and operating devices for said totalizer into connection with which said totalizer is moved by said cam.

9. In a machine of the class described, the combination with a swinging frame and a 45 totalizer and an actuating shaft both carried by said frame, of a cam carried by said actuating shaft, a stationary element with which said cam engages and a main operating device for driving said actuating shaft.

50 10. In a machine of the class described, the combination with a movable frame, and a totalizer and a frame actuating shaft, both carried by said frame, a cam carried by said actuating shaft, a stationary element 55 with which said cam engages, a main operating device for driving said actuating shaft, and driving devices into connection with which said totalizer is moved by said cam.

60 11. In a machine of the class described, the combination with a movable frame, and a totalizer and a transfer operating shaft both carried by said frame, of a cam moved by said transfer shaft, a stationary element

acted on by said cam, a main operating device for said transfer shaft, and driving devices into connection with which said totalizer is thrown by said cam.

65 12. In a machine of the class described, the combination with a swinging frame and a totalizer and transfer mechanism therefor, both carried in said frame, a device moved with said transfer mechanism and having connections for rocking said frame, a main operating device for actuating said transfer mechanism and said frame rocking device, and driving mechanism into connection with which said totalizer is thrown by rocking said frame.

70 13. In a machine of the class described, the combination with a swinging frame, and a totalizer and a frame rocking device, both carried in said frame, a stationary element with which said frame rocking device engages, a main operating device for driving said frame rocking device, and driving mechanism for said totalizer into connection with which said totalizer is thrown by rocking said frame.

75 14. In a machine of the class described, the combination with a movable frame, and a totalizer and a frame actuating device both carried by said frame, of a stationary element with which said frame actuating device engages, a main operating mechanism 80 for driving said frame actuating device, and driving mechanism for said totalizer and into connection with which said totalizer is thrown by actuating said frame.

85 15. In a machine of the class described, the combination with a movable frame, and a totalizer and a transfer actuating device, both carried by said frame, of a frame adjusting element moved with said transfer actuating device, a stationary element co-acting with said frame adjusting element, a main operating device for driving said transfer shaft, and driving devices for said totalizer, and into connection with which said totalizer is thrown by adjusting said frame.

90 16. In a machine of the class described, the combination with a movable frame, and a totalizer and a frame actuating shaft, both carried by said frame, a cam carried by said actuating shaft, a stationary element with which said cam engages, a main operating device for driving said actuating shaft, and driving devices into connection with which said totalizer is moved by said cam, 115 said cam arranged to hold the totalizer normally in mesh with said driving devices.

120 17. In a machine of the class described, the combination with a movable frame, and a totalizer, and a frame actuating shaft, both carried by said frame, a cam carried by said shaft, a stationary element with which said cam engages, a main operating

device, driving devices into connection with which said totalizer is moved by said cam, connections from said main operating device for restoring said driving devices to normal 5 position, and means whereby said main actuating device drives said frame actuating shaft.

This specification signed and witnessed this first of February, 1907.
